DESIGN FOR A COMBINATION DESK UNIT

Max J. Lewis, Forest Hills, N. Y.

Application June 17, 1946, Serial No. 130,811

Term of patent 3½ years

(CL. D74—1)

To all whom it may concern:

Be it known that I, Max J. Lewis, a citizen of the United States, residing at Forest Hills, county of Queens, and State of New York, have invented a new, original, and ornamental Design for a Combination Desk Unit, of which the following is a specification, reference being had to the accompanying drawing, forming part thereof.

In the drawing:

Fig. 1 is a perspective view of the combination desk unit, showing my new design.

Fig. 2 is a side view of the combination desk unit, showing my new design.

The printed matter is merely representative of that which will appear on the calendar from time to time.

I claim:

The ornamental design for a combination desk unit, substantially as shown and described.

MAX J. LEWIS.
